ATTORNEY

UNITED STATES PATENT OFFICE.

IRENE STRABELLE, OF ATLANTIC CITY, NEW JERSEY.

HAIR WAVER.

Application filed December 4, 1926. Serial No. 152,652.

This invention relates to improvements in hair wavers and more particularly to hair wavers constructed of a single length of braided flexible non-elastic material.

5 The primary object of the invention resides in a hair waver of the type above mentioned which is provided with an eye or loop at one end, while the free ends of the same are bound by a ferrule for permitting the 10 ends to be quickly and easily inserted through the eye when applying the waver to the hair of a user.

Another object of the invention is the provision of a hair waver constructed of a 15 single length of flexible material which is bent midway between its ends and twisted together to provide an eye and a twisted body portion, there being a metal collar applied to the body portion adjacent the eye 20 for preventing accidental enlargement or contraction of the same, so that the free end of the body portion may always be inserted therethrough when the device is applied to the head of a user.

25 Another object of the invention is to provide a hair waver of the type mentioned in which the free ends of the material from which the waver is formed are prevented from injuring the head of the user when in 30 position thereon and which affords comfort to the wearer.

With these and other objects in view, the invention resides in certain novel construction and combination and arrangement of 35 parts, the essential features of which are hereinafter fully described, are particularly pointed out in the appended claims, and are illustrated in the accompanying drawing, in which:—

40 Figure 1 is a side elevational view of my improved hair waver.

Figure 2 is an enlarged transverse sectional view on the line 2—2 of Figure 1.

Figure 3 is a similar view on the line 3—3 45 of Figure 1.

Figure 4 is a side elevational view of the hair waver bent into position for use.

Figure 5 is a detail vertical sectional view 50 through the end of the waver.

Referring more particularly to the drawing, the reference numeral 10 designates my improved hair waver in its entirety and which is constructed of a single length of

flexible non-elastic material 11. The material comprises a central core of flexible 55 wire 12 covered by a layer of rubber 13 or other soft pliable material, and which rubber is in turn covered by an outer covering of silk braid or the like 14.

The length of the material 11 is bent midway between its ends to provide an eye or loop 15 while the free ends are twisted together to produce a variable spiral and which constitute the body 16. A metal band 17 encircles the body 16 adjacent the eye 15 60 for preventing the eye from becoming enlarged or reduced by the untwisting or further twisting of the free ends. Briefly, the band is intended to always maintain the eye the same size. The band is tightly fitted 70 about the body to prevent longitudinal movement of the same thereon.

The extreme ends of the material are covered by a tapering ferrule or cap 18 which may be secured thereon in any suitable way such as by baring the ends of the wires 12 and dropping solder into the cap with the ends of the wire embedded therein. The diameter of the ferrule at its largest point is such as to freely pass through the 80 eye or loop 15 after the hair to be waved has been wrapped about the body in the usual manner after which the body is bent as shown in Figure 4 of the drawing with the ferrule inserted through the eye, and the 85 free end bent so as to retain the waver upon the head of the user.

From the foregoing description, it will be seen that I have improved upon the well-known type of hair waver herein mentioned by applying thereto a metal band for maintaining the size of the eye, and a ferrule for binding the free end of the same to prevent injury to the head of the user, as it will be appreciated that when the ends of 95 the wire are left bare, the same are liable to scratch the scalp of the user. The device also affords a more comfortable waver than those heretofore placed upon the market, and unlike others, when closed, the same 100 cannot become accidentally unfastened.

While I have described what I deem to be the most desirable embodiment of my invention, it is obvious that many of the details may be varied without in any way departing from the spirit of my invention,

2
and I therefore do not limit myself to the exact details of construction herein set forth nor to anything less than the whole of my invention limited only by the appended 5 claims.

What is claimed as new is:—

1. A hair waver comprising a body of flexible material having a metallic core, said body being doubled upon itself to provide 10 an eye, and the free ends twisted together, means for maintaining the size of said eye, and a ferrule encircling the extreme ends of flexible material for holding the same together, said ferrule adapted to freely pass 15 through said eye when applying the waver to the hair of a user.
2. A hair waver comprising a body of flexible material having a metallic core, said body being doubled upon itself to provide an 20 eye, and the free ends twisted together, means for maintaining the size of said eye, a collar fitted tightly about said body adjacent said eye, and a ferrule encircling the extreme ends of flexible material for holding 25 the same together, said ferrule adapted to

freely pass through said eye when applying the waver to the hair of a user.

3. A hair waver comprising a single length of flexible non-elastic material bent midway between its ends and twisted together to provide an eye and a twisted body portion, a collar encircling said body adjacent said eye for maintaining the size of said eye, and a ferrule receiving the free ends of said material for bunching the same for insertion 30 through said eye.

4. A hair waver comprising a single length of non-elastic metallic core having a covering of soft flexible material thereon, said core being bent midway between its ends and 40 twisted together to provide an eye and a twisted body, a collar fitted about said body adjacent said eye to maintain the size of the same, the extreme ends of said core being bare, and a ferrule secured to and receiving 45 the bare ends of said core.

In testimony whereof I have affixed my signature.

MRS. IRENE STRABELLE.
